RAILWAY DINING CAR

Obey N. Erlenmeyer, Clifton, N. J.

Application December 7, 1954, Serial No. 33,431

Term of patent 14 years

(Cl. D66—1)

Fig. 1

Fig. 2

Figure 1 is a plan view of a railway dining car embodying my new design.

Figure 2 is a side view thereof.

Figure 3 is a perspective view illustrating a portion of the dining car.

Figure 4 is a plan view of the portion of the dining car shown in Figure 3.

The characteristic features of my design reside in that portion of the dining car which is shown in Figure 3 of the drawings.

I claim:

The ornamental design for a railway dining car, as shown and described.
